TO NEW PROCESS OIL COMPANY, OF ST. LOUIS, MISSOURI, A CORPORATION OF MIN-
NESOTA.

PROCESS OF TREATING HYDROCARBON OILS.

1,138,266.

Specification of Letters Patent.

Patented May 4, 1915.

Application filed March 24, 1913. Serial No. 756,433.

To all whom it may concern:

Be it known that I, CHARLES H. WASHBURN, a citizen of the United States of America, and resident of the city of St. Louis and State of Missouri, have invented certain new and useful Improvements in Processes of Treating Hydrocarbon Oils, of which the following is a full, clear, and exact description, reference being had to the accompanying drawings, forming a part of this description.

My invention relates to a process of treating kerosene and the heavier petroleum products in such manner as to produce a product which has a higher flash point than gasolene, is heavier than gasolene or naphtha, and which, being derived from kerosene and the heavier petroleum products after the distillation of gasolene and naphtha, is much less expensive than gasolene and naphtha.

The object of my invention is to produce a hydrocarbon product that, being less explosive than gasolene, and of inexpensive nature, is suitable for use with safety in many instances where gasolene and naphtha are now utilized, and in other instances where the use of such gasolene and naphtha has been largely discontinued owing to the danger in using them.

It is a fact well known to oil refiners that, when petroleum fuel oil or gas oil is cracked to produce light products, the light products produced have an exceedingly offensive odor that unfit them for general use, and no method has heretofore been found, so far as I am aware, to crack such oils to a kerosene product ranging from 40° to 48° Baumé and not from large quantities of the light hydrocarbons, gasolene and naphtha, all having more or less offensive odors. I have discovered that when kerosene, or heavier petroleum fuel or gas oils are mixed with water and then heated in a suitable retort, and back pressure is maintained in said retort, and an equal pressure maintained upon the vapors themselves during the process of condensation, both in the retort and in the condenser, I am enabled to obtain a product, free from the offensive odors of the initial products, and suitable for use in lieu of the more expensive light products. Such product is, furthermore, produced without the formation of large quantities of light hydro-

carbons, as in most processes heretofore known.

In practising my process, I introduce hydrocarbon oil and water in suitable proportions into a retort heated in any suitable manner to the desired temperature; for example, say, 600° F. to 800° F., within the 60 retort when treating petroleum gas oil alone; and, for example, in treating kerosene, from 800° F. to 950° F., within the retort maintaining at the same time, in the retort and against the resulting vapors and 65 condensed products, a pressure of three to five atmospheres. The proportional quantities of oil and water depend upon the initial product, and may be easily determined in practice from the product derived by following my process. When using petroleum gas oil or fuel oil while following my process, I preferably use four parts of oil to one part of water; and, when kerosene is used, I preferably use at least equal parts 75 of kerosene and water, in which connection I would state that the lower the proportion of water, all things considered, the easier the oil will crack. Therefore inasmuch as it is necessary to crack gas oil to a greater 80 degree than kerosene in producing my product, I use a less proportion of water with gas oil and crack the oil to substantially the same point as kerosene is cracked to with a greater proportion of water, as specified. 85

My process is preferably carried out in an apparatus such as that illustrated in the accompanying drawing, which is a diagrammatical view of the apparatus.

B designates a retort, and A a furnace in 90 which fuel of any suitable description may be burned to heat the retort and its contents. The retort B is preferably arranged in inclined position in the furnace so that its inlet end is highest. An inlet pipe C 95 leads into the forward end of the retort B.

D and E designate, respectively, petroleum oil and water conducting pipes connected to the inlet pipe C, the pipes being preferably provided with check valves F, 100 which prevent back flow of the oil and water, and with cut off valves G, by which the flow of oil and water may be discontinued.

H and I designate, respectively, storage 105 tanks for oil and water supplied to the pipes

D and E, these tanks being preferably located at a higher level than the retort B. The supply of oil and water in the storage tanks is maintained by delivery pipes *h* and 5 *i* leading to the respective tanks, the pipes being provided with cut off valves *h'* and *i'*.

J is a steam conducting pipe, through 10 which steam under pressure may be delivered to the oil and water tanks H and I to exert a pressure against the contents of said tanks, and cause the oil and water therein to be delivered under the desired pressure through the pipes D and E and the 15 inlet pipe C to the retort B. The pipe J is supplied with a cut off valve *j* and a pressure gage *j'*.

A pressure gage K is connected to the oil 20 and water conducting members at the location of the inlet pipe C to indicate the pressure exerted upon the oil and water delivered to the retort.

L designates a condenser coil that is subjected to the cooling action of water 25 discharged thereonto from a sprinkler pipe M located over the coil.

Communication between the outlet end of the retort B and the condenser coil is established by a connecting pipe N, through which 30 the product produced in carrying out my process is delivered to the condenser to be condensed and discharged through the terminal of the coil into a suitable closed receiver O, supplied with an air or gas relief 35 valve *o*. The pipe N is preferably supplied with a cut off valve P. I also preferably provide a pressure gage R that indicates the pressure of the product passing through the pipe N when the apparatus is in service, and 40 a safety valve S that will open when there is excess of pressure in the retort B.

In the practical use of the apparatus herein described to carry out my process, petroleum oil and water in the proper proportions, as specified, and under a pressure, as 45 previously indicated, are delivered through the inlet pipe C into the retort B. The retort and its contents are heated to the desired temperature, according to the nature of 50 the petroleum product being treated, as I have previously noted, under a pressure, as previously stated, of from three to five atmospheres. With these points in mind, and the fact also being considered that the condenser is kept closed at its terminal, as 55 stated, it will be understood that vaporization of the kerosene, or heavier petroleum product occurs, the vapors passing to the condenser coil L, where they are condensed and confined. The terminal of the condenser, being closed, there is resultant accumulation of vapors adjacent said terminal, 60 a back pressure is created and maintained in the condenser and also in the retort, in sequence of which and the pressure exerted 65

at the inlet end of the retort, an equal pressure is maintained upon the vapors in both the retort and condenser, with resultant production of my product.

The existence of the back pressure, as 70 stated, will be more fully understood when it is explained that three volumes of pressure are created in the retort of an apparatus used for the production of my product, one of these volumes of pressure being obtained 75 from the conversion of water into vapor, and the other two volumes of pressure being obtained from the breaking up of the petroleum product under treatment. These three 80 volumes of pressure, when produced in the retort, pass from the retort to the condenser, and, upon reaching the terminal of the condenser, accumulate thereat, with the result of 85 affording the back pressure to which I have referred.

I am aware that it is old to use oil and water together in heated retorts to derive 90 gasoline or other light hydrocarbons, and that hydrocarbon oil has been heated under pressure of 3 to 5 atmospheres to obtain 95 gasoline and other light hydrocarbons, but I believe it to be new with me to follow a process in which hydrocarbon oil and water are used together in a heated retort, with the resulting vapors in the retort and the 100 condenser maintained under a pressure for the purpose of obtaining a petroleum product that is heavier than gasoline or naphtha.

In conclusion I desire to add that the essential features of the present process are 100 temperature, plus pressure, plus neutral medium (steam) to avoid destructive distillation. The pressure used serves to crack the oil, the temperature facilitates the cracking operation and the addition of the neutral medium with the pressure and temperature obviates destructive distillation. One of the most important features of the present process is the pressure created due to the 105 terminal of the condenser being closed, owing to which the desired pressure is maintained in both the retort and the condenser. In this connection it is to be noted that the receiver O is considered as the terminal of the condenser in the apparatus shown. There is no escape from this receiver while 110 the apparatus is in operation, the receiver being supplied with only a gas relief valve *o*, which opens for safety purposes only.

I claim:—

1. The process of treating kerosene and heavier products of petroleum, which consists in placing the petroleum product and water into a retort, converting them into vapor, and leading off the vapor to a condenser, the terminal of which is closed to create a back pressure against the vapor, thereby condensing the vapor under a pressure of from three to five atmospheres maintained in both the retort and the condenser. 120

2. The process of treating kerosene and heavier products of petroleum, which consists in introducing the petroleum product and water into a retort under pressure, converting the product and water into vapor, and leading off the vapor to a condenser, the terminal of which is closed to create a back pressure against the vapor, thereby condensing the vapor under a pressure of from three to five atmospheres maintained in both the retort and the condenser.
3. The process of transforming petroleum oils of a Baumé of 26° to 48° into a product of a Baumé not exceeding 52° , which consists in passing oil and water in liquid form into a retort, converting the oil and water into vapor, and leading off the vapor to a condenser, the terminal of which is closed to create a back pressure against the vapor, thereby condensing the vapor under a pressure of from three to five atmospheres maintained in both the retort and the condenser.
4. The process of transforming petroleum oils of a Baumé of 26° to 48° into a product of a Baumé not exceeding 52° , which consists in passing oil and water in liquid form into a retort, converting the oil and water into vapor by subjecting them to 600° F. to 950° F., and leading off the vapor to a condenser, the terminal of which is closed to create a back pressure against the vapor, thereby condensing the vapor under a pressure of from three to five atmospheres maintained throughout distillation and condensation.

sure of from three to five atmospheres maintained throughout distillation and condensation.

4. The process of transforming petroleum oils of a Baumé of 26° to 48° into a product of a Baumé not exceeding 52° , which consists in passing oil and water in liquid form into a retort, converting the oil and water into vapor by subjecting them to 600° F. to 950° F., and leading off the vapor to a condenser, the terminal of which is closed to create a back pressure against the vapor, thereby condensing the vapor under a pressure of from three to five atmospheres maintained throughout distillation and condensation.

CHARLES H. WASHBURN.
